UNITED STATES PATENT OFFICE.

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY.

THREAD-HANDLING MACHINE.

Application filed April 11, 1921. Serial No. 460,531.

To all whom it may concern:

Be it known that I, FRED N. LA CHAPELLE, a citizen of the United States, residing at Beverly, in the county of Essex 5 and State of Massachusetts, have invented certain new and useful Improvements in Thread-Handling Machines; and I do hereby declare the following to be a full, clear, and exact description of the invention, such 10 as will enable others skilled in the art to which it appertains to make and use the same.

The present invention relates to thread handling machines and more particularly 15 to machines of this type for inserting a thread fastener through the upper and insole lip of a lasted shoe.

As is well known to those skilled in the art, the metallic fasteners which serve to 20 hold the upper in lasted position are sometimes replaced prior to the inseam sewing operation by thread fasteners extending through the upper and insole lip of the lasted shoe. These thread fasteners merely 25 serve as temporary holding devices between the lasting and sewing operations and accordingly it is desirable that the insertion of the thread fasteners may be accomplished as simply and expeditiously as possible.

One object of the present invention is to 30 provide a new and improved form of thread handling machine by virtue of which the operation of forming and inserting these thread fasteners is materially improved.

With this object in view one feature of 35 the invention contemplates the provision of means for passing a loop of thread through the work and means for compacting or upsetting the loop of thread thus formed within the work. It has been found that by 40 thus upsetting the loop of thread, especially where a wax thread is employed, the opening within the work is completely filled by the thread plug and the fastener is held 45 firmly within the work.

An additional feature of the present invention contemplates the formation of a tongue in the work which aids in holding the fastener in place both during and after 50 its formation in the work. In the simplest and most efficient form of the invention which has yet been devised an eye needle is provided with a substantially U-shaped cutting edge which forms a tongue in the work

during its advancing movement and thereafter passes a loop of thread through the opening left by the tongue. Upon withdrawing the needle, a loop of thread is retained in the work by frictional engagement of the tongue therewith. When the 60 thread plug is thereafter compacted or upset a fairly secure lock results.

Still further features of the invention consist in certain novel features of construction, combinations and arrangements of 65 parts hereinafter described and claimed, the advantages of which will be obvious to those skilled in the art from the following description.

In the accompanying drawings illustrating the preferred form of the invention Figure 1 represents a side elevation of a machine embodying the several features of the invention; Fig. 2 is a front elevation of the machine shown in Fig. 1; Fig. 3 is a 70 detail illustrating an elevation partly in section of the improved form of needle; Fig. 4 is an end view of the needle shown in Fig. 3; and Fig. 5 is a partially diagrammatic view illustrating the manner in which the 75 loop of thread is held within the work and compacted by the ram or plunger.

The illustrated embodiment of the invention discloses a machine intended primarily for operation upon a lasted boot or shoe, as 80 indicated generally at 10, having an insole 11 and an upper 12 lasted thereto. During the operation of inserting the thread fasteners the shoe is held, as shown, by a 85 stationary channel guide 14 adjustably mounted upon the lower end of a post 15 forming a part of the machine frame. Co-operating with the channel guide is a back gage 16 which is secured to the forward end 90 of a slide bar 18 which is reciprocated in the machine frame by an arm 19 depending from a rock shaft 20. The lower end of the arm 19 engages with a lateral extension 22 formed upon the rear end of the slide bar to retract the back gage at predetermined 95 intervals. The arm 19 is connected with a second arm 23 which is operatively connected with a cam path formed in the face 24 of the cam disk 26. The construction is such that the back gage is yieldingly engaged with the work through the action of the spring 28 in the usual manner to permit the back gage to accommodate itself to vary-

100
105

ing thicknesses of the work. The rearward movement of the back gage to release the work is positively accomplished by engagement of the arm 19 with the extension 22, as 5 is usual in this class of machines.

The formation and insertion of the thread fastener within the work is accomplished by a straight eye needle having a substantially U-shaped cutting edge. This needle during 10 its advancing movement forms a U-shaped incision in the work and passes a loop of thread therethrough, after which it is withdrawn, leaving the loop of thread engaged in the work. Subsequently the loop of 15 thread is severed from the supply and is compacted or upset in the work by a ram or plunger engaging with the thread loop upon the outside of the work. A straight eye needle 30 is secured in the end of a slide 32 supported for movement in inclined ways 20 formed in the machine frame. As will be observed from an inspection of Fig. 1, the needle in its advance moves transversely of the work and in a downward direction from 25 the outside of the upper toward the inside of the insole lip. The needle is provided with a substantially U-shaped cutting edge 34 for the formation of a tongue in the work and an eye 36 through which the thread 30 passes. The needle slide 32 is conveniently provided with an upward extension 38 operatively connected with a cam path formed 35 in the face 40 of the cam disk 42. The cam path is designed to impart a reciprocating movement to the needle during each rotation of the main shaft 44. The thread is led from the wax stripper, indicated at 46, over a guide roll 48 about which it makes one complete turn and thence through a guide 40 50 to the eye of the needle. In order to measure off sufficient thread for the formation of each loop a ratchet toothed wheel 52 is secured to the guide roll and is operated by a drive pawl 54 pivoted to an arm 45 56 mounted upon the rock shaft 20 and connected through a second arm 58 with a cam path formed in the face 59 of the cam disk 60. This mechanism is designed to rotate the guide roll and draw off a supply of 50 55 thread sufficient for the formation of a single loop. As will be observed from an inspection of Fig. 5, the needle upon its advancing movement forms a tongue in the upper and insole lip and passes a loop of 60 65 thread through the opening left by these tongues. When the needle is withdrawn, the tongues frictionally engage with the short end of the loop which lies in the lower portion of the needle and prevent the withdrawal of the loop with the needle. After the needle has been withdrawn into the position shown in Fig. 1, a thread cutter 62 pivoted upon the back gage at 64 is operated to sever the thread from the supply. This 65 thread cutter is operated in the usual man-

ner through a slide 65, an arm 66 pivoted upon the shaft 20 and operatively connected through a second arm 68 with a cam path formed in the face 70 of the cam disk 60.

After the loop of thread has been severed 70 from the supply a plunger or ram 72 is advanced through the back gage into engagement with the loop of thread at the point where it emerges from the upper. This ram, as shown in Fig. 5, is provided with a cup-shaped working end 74 to upset the end of the thread loop and compact the wax thread within the opening. The action of this plunger spreads out the fastener within the opening and tends to form a locking head 80 upon the outer end of the fastener in a manner to securely hold the parts of the work together. As will be observed from an inspection of Fig. 1, the plunger 72 is secured in the outer end of a slide 76 which is operatively connected at its rear end with an arm 78 through a rack 80 formed upon the slide and cooperating with a gear segment 82 formed upon the lower end of the arm. The arm 78 is actuated by a second arm 84 90 which is operatively connected with a path cam formed in the face 86 of the cam disk 42, as shown in Fig. 2. This cam is designed to advance the plunger into engagement with the loop of thread after the needle has 95 been withdrawn from the work and the thread severed from the supply. Thereafter the plunger and back gage are withdrawn to permit feeding the work into a new position. In the illustrated embodiment of the invention, the work is automatically fed between the completion of one thread fastener and the starting of the next succeeding thread fastener by a feed point 90 engaging the channel of the insole at one side of the channel guide. This feed point depends from a slide 92 supported upon parallel guide rods 93 and 94. The slide is reciprocated to move the feed point in the direction of feed 100 through a lever 95 fulcrumed at 96 and connected at one end with an extension 97 forming a part of the slide 92. The opposite end is provided with a cam roll 98 which is received in a cam path formed in the periphery 99 of the cam disk 26, as shown in Figs. 115 and 2. The feed point is moved into and out of engagement with the work by oscillating the head 92 through an arm 100 having a forked outer end 101 which straddles a pin 102 secured in the outer end of a rocker 110 arm 103. The rocker arm is connected with a hub 104 having a second arm 105 operatively connected with a cam path formed in the face 106 of the cam disk 26. With this construction the desired four motions 120 are imparted to the feed point to intermittently advance the work between the formation and insertion of the thread fastener. It will be observed that this advancing movement of the work takes place during the 130

time that the back gage is retracted and the work thereby released from the clamping effect of this member.

While it is preferred to employ the specific construction and arrangement of parts shown and described it will be understood that this construction and arrangement is not essential except so far as specified in the claims and may be changed or modified without departing from the broader features of the invention.

The invention having been described, what is claimed is:

1. A thread fastening machine comprising an eye needle having a cutting edge designed to form a tongue in the work, means for actuating the needle to pass a loop of thread through the work, means for severing the thread, and means for compacting 20 the loop of thread in the work.

2. A thread fastening machine comprising a straight eye needle, means for actuating the needle to pass a loop of thread through the work, means for severing the 25 loop of thread from the supply, and means for compacting the loop of thread in the work.

3. A thread fastening machine comprising means for forming a tongue in the work, means for passing a loop of thread through 30 the opening created by the formation of the tongue, means for severing the loop of thread from the supply, and means for upsetting the loop of thread thus formed in 35 the work.

4. A thread fastening machine comprising a straight eye needle having a substantially U-shaped cutting edge, means for actuating the needle to form an incision in the 40 work and to pass a loop of thread therethrough, means for severing the loop of thread from the supply, and means for compacting the loop of thread upon one side of the work.

5. A thread fastening machine comprising work positioning members, a needle, mechanism for actuating the needle to pass single loops of thread successively through the work, means for severing each loop of thread from the supply, and means for feeding the work. 45 50

6. A thread fastening machine comprising a channel guide and a cooperating back gage, a needle, means for actuating the needle to pass a single loop of thread 55 through the upper and insole lip of a lasted shoe, means for severing the loop of thread thus formed from the supply, and means for feeding the work between the advancing movements of the needle to cause the insertion of the single thread loops at substantially uniform intervals about the shoe. 60

7. A thread fastening machine comprising work positioning devices, a needle provided with a U-shaped shank terminating 65 in a similarly formed cutting edge and with an eye disposed back of the edge, and means for actuating the needle to form a tongue in the work and to pass a loop of thread through the opening left by the tongue. 70

8. A thread fastening machine comprising a channel guide and a cooperating back gage, a needle, means for advancing the needle through the work from the outside of the upper to pass a loop of thread through 75 the upper and insole lip, means for severing a loop of thread from the supply, and a plunger adapted to engage with the loop of thread from the outside and compress the loop in the work. 80

9. A thread fastening machine comprising a needle having a cutting end designed to form an incision in the work, means for actuating the needle to pass a loop of thread through the incision thus formed, means for severing the thread, and means for compacting the loop of thread in the work. 85

FRED N. LA CHAPELLE.
